UNITED STATES PATENT OFFICE.

CHARLES H. CAMPBELL, OF BROOKLINE, MASSACHUSETTS, ASSIGNOR TO CHARLES H. CAMPBELL, OF BROOKLINE, MASSACHUSETTS, AND HAROLD B. CAMPBELL, OF CAMBRIDGE, MASSACHUSETTS, COPARTNERS DOING BUSINESS AS COLONIAL CAN CO., OF BOSTON, MASSACHUSETTS.

PANE RETAINER.

Application filed February 7, 1924. Serial No. 691,125.

The present invention relates to means for holding a pane of glass or similar light transmitting body in a frame. It is particularly designed and intended for display tops of cans or boxes in which goods such as crackers are displayed for sale in stores. Such display tops are commonly made of a frame which encloses and rests upon the upper edge of an open cracker box, and a cover hinged to such frame. The cover has a large opening, or a number of openings, in order that the goods may be seen, and such opening is covered by a pane of glass. Such a cover is included within the meaning of the term "frame" as used in this specification, and so also are other frames adapted to hold and carry a transparent pane, for whatever use the same may be provided.

For convenience of description, and because the present invention has been designed particularly for use in a cover for cracker boxes or for the display tops of such boxes, I will from now on generally refer to the structure in which the form of my invention herein illustrated is embodied, as a cover; without, however, intending to imply thereby any limitation in the scope of my claimed invention beyond those imposed by the prior art.

The object of the invention, briefly stated has been to provide in connection with such a cover or equivalent frame, a simple and inexpensive device for retaining the transparent pane in place; one which will hold the pane firmly and without looseness or opportunity for rattling but in a resilient manner which will allow the cover to be somewhat violently opened and closed without liability of breaking the pane; and yet one which can be easily displaced or removed, and replaced when breakage of the pane requires substitution of a new pane.

The transparent panes used in the environment herein described are almost universally of glass, for which reason I will assume that the pane illustrated in this specification is of that material, but this assumption is not a limitation of the invention, since all other transparent materials are included within the scope of the protection which I claim.

In the drawings herewith I have shown two of the possible embodiments of my in-

vention, in one of which the pane retainer is separable from the cover or frame, and in the other in which the retainer is pivoted to the frame in a manner which prevents its complete removal while permitting such displacement or partial removal as will allow a pane to be easily set in and removed from the frame.

Figure 1 is a plan view of the underneath or inner side of a cover embodying the first mentioned form of the invention.

Fig. 2 is a sectional view taken on the line 2—2 of Fig. 1.

Fig. 3 is a view similar to Fig. 2, showing the second mentioned form of the invention.

Fig. 4 is a fragmentary sectional view taken on the line 4—4 of Fig. 3 and showing one of the possible modes of pivoting the pane retainer in the frame.

Like reference characters designate the same and duplicate parts wherever they occur in all the figures.

As previously stated, the specific frame illustrated is a square cover adapted to be hinged to a cracker can or box, or to a frame provided to fit around the upper end of such a can or box in a well known way. The letter *a* designates the side walls or members of the cover, and *b* represents the top wall, of which the central part is entirely removed to leave an opening or window nearly as large in area as the entire cover. In more general terms the parts *a* may be described as the sides of the frame, and the part or parts *b* as a ledge extending inwardly from the several members of the frame and adapted to support the edges of the transparent pane. *c* represents a pane of glass, or other transparent material, which is placed against the ledge *b* and is held there by a retainer *d*.

The retainer is made of a stiff, but at the same time elastic and resilient material, preferably of mild steel or iron wire, the gauge of which is selected to furnish the required degree of stiffness and resilience according to the service required; that is as to whether the frame is relatively large or small, the glass pane is heavy or light, and to the amount of knocking about to which the combined article may be subjected. Such wire is bent so as to conform to three sides of the frame and to fit within the frame

substantially as shown in Figure 1. The middle part d^1 of the retainer is adapted and intended to lie close to one member of the frame, which for convenience I may call 5 the front member; while the side portions of the retainer, at least as to their extremities, lie close to the members of the frame adjoining the front member; that is, close to opposite side members of the frame. The 10 last mentioned parts of the retainer are bent between their ends to form offsets d^2 of substantial length. These offsets are not in the plane established by the side and middle parts of the retainer, but are inclined or disposed on a bevel with respect to such plane. Thus while the offset part 15 of each side member of the retainer is set over toward the opposite side member, the two offset portions are also both set over toward the pane-supporting ledge of the frame, that is, to the same side from the plane of these side members. At the opposite ends of each offset portion are angles d^3 and d^4 which are adapted to bear on the 20 pane as will presently appear.

That part of the frame which has been called the front member is provided with lugs or catches $e—e$; the opposite or back member of the frame is provided with lugs 25 or catches $f—f$; and the intermediate side members of the frame are each provided with a single lug or catch g near to the back member, or rear wall, of the frame. When the frame is made of sheet metal, as 30 is the case in the present illustration, such lugs or catches are formed by integral parts of the frame walls cut and struck out by suitable dies. In their preferred form, the lugs are made by cutting the material of 35 the frame on a line which may be straight or curved, but is preferably convex, and by offsetting the material of the wall inwardly with a spherical formation between the cut and the curved line where the lug joins the 40 wall. Such curved junction line is indicated at h in Fig. 2. The lugs are thus curved or arched in all planes of section from the junction line to the free edge, designated k in Figure 2, and are very strong and rigid. 45 They cannot be bent or displaced by application against their offset cut edges of any force less than enough to tear the metal.

The cut edges of the lugs, being thus 50 offset from the adjacent walls of the frame, serve as abutments which extend across and interlock with the several parts of the retainer which they engage thus anchoring them to the frame. Such lugs or abutments (except the lugs f, f) face toward the plane 55 of the ledge b , but are separated therefrom far enough to admit the retainer, with its offset portions, between them and the transparent pane; while the lugs f on the rear wall face toward the adjacent side walls of 60 the frame, and so are adapted to hold the 65

extreme ends of the pane retainer and prevent such ends from springing away from the side walls.

In mounting a pane in the frame thus described, the frame is placed with its supporting ledge downward and the pane is laid on such ledge. The retainer is then applied by placing its free ends between the side members of the frame and against the pane or supporting ledge, and pushing the ends toward the rear wall of the frame until they pass under the lugs g and between the lugs f and the adjacent sides of the frame. Thus the ends of the frame are held by the lugs f from springing away from the lugs g , and are retained by the latter in their proper relation to the pane. Finally the middle portion of the retainer is passed down inside of the front wall of the frame and past the lugs $e—e$ on said wall, until it snaps over the edges of such lugs. Such middle portion fits so closely within the front wall that it is deflected by the bulged lugs in being moved past them, and thereupon its resilience causes it to spring out under the ends of the lugs after passing them. The retainer is now securely locked in the frame, and the angles d^3 and d^4 of its offset portions bear on the inner face of the pane near opposite edges of the latter.

The distance to which the parts d^2 of the retainer are offset from the plane of the retainer toward the glass is somewhat greater than the distance of the lugs e and g from the plane of the glass, and this relation causes the retainer to be sprung out of the true plane in being engaged with the glass and with the lugs as described. Hence, the only parts of the retainer which bear on the glass are the angles d^3 and d^4 of the offset portions, and such portions between these angles are sprung away from the glass as shown in Figure 2. Between the angles d^3 and the lugs e , the retainer is sprung toward the plane of the glass, and the middle part d^1 between the lugs e is also sprung or bowed toward the glass. This disposition of the retainer and the holding lugs establishes the bearing points of the retainer on the glass at definitely known points, that is, the locations of the angles d^3 and d^4 , and it causes these angles to bear with a spring pressure on the glass, lending the resilience and elasticity of all the parts of the retainer to press the glass firmly against the ledge b of the frame, but permitting them to yield when force is applied to the glass from outside of the frame.

For example if a cracker can cover containing this invention is slammed shut hard, the momentum of the glass might break it if it were rigidly fastened in the frame, but the yielding nature of the retainer softens such shocks and protects the glass from

breakage. In the same way the glass can stand heavy pressures and blows from external objects without breaking.

The second mentioned form of the invention, shown in Figs. 3 and 4, is identical with that just described in detail, with the single exception that the ends of the retainer are pivoted to the side walls of the frame near the back wall, instead of being detachably held in the frame; and are thus anchored to, or interlocked with, the frame in a permanent way. The form of pivot shown in Fig. 4 consists in punching, offsetting inwardly, and rolling the metal of the frame to provide a tubular formation at *l*, Fig. 4, similar to a hollow rivet, and by bending the end of the retainer to form an eye *m* which fits the pivot *l* and is adapted to turn thereon. Both free ends of the retainer are treated and held in this manner. Of course other and equivalent means for pivotally connecting the retainer to the frame may be used and are within the scope of the protection of the claim, as for instance, inserting a separate rivet in the wall of the frame and through the eye *m*, or by bending out the end of the retainer so as to form in itself a pivot seated in a hole in the frame, or by other means known to those skilled in the art.

It will be understood that in order to disengage the retainer shown in Figs. 3 and 4, from the glass, all that is needed is to free the middle part of the retainer from the lugs *e*, and then swing the retainer as a whole about its pivots away from the glass. Although the pivoted ends of the retainer still remain in the frame, plenty of room is left for inserting and removing the glass, moving it edgewise in an inclined path. Then in setting the retainer to hold the glass, it is swung about its pivots until the middle portion snaps past the lugs *e*. The same springy quality exists between the angles *d*³ of the retainer and the part which is anchored by the lugs *e*, and also between the angles *d*⁴ and the pivoted ends of the retainer, as already described.

What I claim and desire to secure by Letters Patent is:

1. The combination with a frame having a pane supporting ledge and side walls, of a retainer consisting of a wire bent to lie

close within two of the opposite side walls and an intermediate wall of the frame, the extremities of the wire being interlocked with the frame, and said intermediate wall of the frame having inwardly projecting abutments adapted to engage the adjacent part of the retainer and limit separation thereof from the plane of the pane, the side portions of the retainer being offset toward one another and toward the plane of the pane at the same time, said offset part having separated angles arranged to bear against the pane, and being sprung away from the frame between said angles, when the middle part of the retainer is so interlocked with the adjacent part of the frame.

2. The combination of a frame having a pane supporting ledge, a pane bearing against said ledge, and a resilient pane retainer; said retainer being an elongated resilient member formed to be within and generally beside two opposite sides and an intermediate side of the frame, the extremities of the retainer and its middle portion being anchored to the frame at points spaced back from the pane, and the side portions of the retainer having offset angles arranged to engage the pane and being so far offset as to cause the parts of the retainer between its points of engagement and anchorage to be so stressed that said engaging points are pressed resiliently against the pane and toward the ledge.

3. The combination with a frame having a pane supporting ledge and side walls, of a retainer consisting of a wire bent to lie close within two of the opposite side walls and an intermediate wall of the frame, the major part of the retainer being normally out of contact with the pane lying against said ledge, abutments on the said walls arranged to interlock with said retainer and prevent accidental withdrawal of the retainer from the pane, the side portions of said retainer being offset between their ends toward the said ledge far enough to exert a constant resilient pressure against the pane at separated points, holding the latter against said ledge.

In testimony whereof I have affixed my signature.

CHARLES H. CAMPBELL.
